COLLAR STUD TO BE SEWN

Hermann Lewy, Berlin-Charlottenburg, Germany

Application May 4, 1937, Serial No. 140,715
In Germany June 19, 1935

1 Claim. (Cl. 24—97)

This invention relates to a collar stud to be sewed on the neck band of the shirt without impeding washing and ironing.

The invention is substantially characterized in that the stud stem and the stud head can be folded down and are thus accommodated in full length within the rim of the base to be sewn on. The stud head can be either rigid or resiliently foldable, and the stem is hingedly mounted on the base somewhat offset from the center of the same.

An embodiment of the invention is illustrated by way of example in the accompanying drawing, in which Fig. 1 is a plan view of the collar stud attached to a shirt and showing the stem in folded position. Fig. 2 is a side elevation of the folded collar stud, detached. Fig. 3 is a view similar to Fig. 1 showing the stem in raised position. Fig. 4 is a side elevation of the stud shown in Fig. 3, detached. Fig. 5 is a view similar to Fig. 3 but showing the head of the stud in the position ready for use. Fig. 6 is a side elevation of the stud shown in Fig. 5, detached.

The base *a* is provided with holes, preferably four holes, to facilitate the sewing of the base on the neck band of the shirt. Base *a* is of disc shape and the rim is slightly curved upwards. On the base *a* a stem *d* is hingedly mounted by means of a spring hinge *c*. The head *e* of the stud is fixed on the outer end of stem *d*, also by means of a spring hinge similar to that by which the stem is mounted on the base *a*, so that when the stem *d* is raised into the position shown in

Figs. 2-6, it is automatically securely held in this position, same as the stud head *e*, which can either be folded down against the stem, as shown in Figs. 1-4 inclusive, or which can be folded into operative position as shown in Figs. 5 and 6.

Fig. 3 shows the blade spring *f* for the folding hinge *c*.

Several modifications are possible without departing from the scope of the invention. The rim of the base *a* can for instance be cut away for 10 accommodating the stem *d* and head *e*.

In Fig. 2 the stem *d* and head *e* are shown slightly lifted out of the plane of the base *a*. This is done merely to show more clearly the construction of the collar stud. In reality stem *d* and head *e*, when folded down, lie upon the base *a* so that they do not project over the upwardly curved rim of the base *a*. If the head *e* is rigidly fixed on stem *d* it is preferably ball-shaped. If the base *a* is of larger diameter the point at which the stem is hingedly fixed may be disposed closer to the center of base *a*.

I claim:—

A collar stud comprising in combination a base with upwardly bent rim, a stem hingedly mounted eccentrically on said base, and a head hingedly mounted on the outer end of said stem, said stem when in folded positions lying below the plane of the rim, and said base having holes therein when same can be sewed upon the neck band of a 30 shirt.

HERMANN LEWY.
